UNITED STATES PATENT OFFICE.

WILSON AULL, JR., OF NEW YORK, N. Y., AND HARRY W. HOUCK, OF EAST ORANGE, NEW JERSEY, ASSIGNEES TO RADIO INVENTIONS, INC., OF NEW YORK, N. Y., A CORPORATION OF NEW YORK.

VARIABLE TUNING INDUCTANCE DEVICE.

Application filed September 6, 1922. Serial No. 586,422.

This invention relates to radio frequency tuning devices.

An object is the provision of suitable apparatus for a variable radio frequency inductance or transformer, as the case may be, which can be easily and quickly operated to effect adjustments corresponding with the wave length of any desired signal.

To these ends the invention contemplates 10 a plurality of adjacently mounted coils of the well known honeycomb or duolateral type enclosed in a suitable container consisting of two circular end plates connected together by a cylindrical shell. An arcuate row of terminals 15 is mounted on one of the end plates and taps from the several coils are brought out to the fixed terminals.

The inductance units are provided with a common rotatable shaft which extends 20 through their several axes and a plurality of contact arms are secured to and electrically connected to the shaft. Each of these contact arms is individually connected to one of the inductance units and is arranged to wipe 25 over the fixed contacts thereof when the shaft is rotated.

The inductance unit, per se, and the assemblage comprising a plurality of such units, includes a number of novel features. One of 30 these features resides in the form of construction wherein several coils, preferably of the honeycomb or duolateral type, are each wound on short tubes of fibre or other suitable material and mounted side by side on a longer 35 supporting tube. Another feature resides in the form of construction wherein two end plates are provided each having an annular groove in one of its faces into which one end of the supporting tube is seated and secured 40 by an adhesive such as ordinary glue. A metallic shell, preferably in the form of a cylinder, connects the two end plates together thereby forming a complete enclosure for the coils and supporting tube. The several coils 45 are connected together and taps are brought out from their junctures and extremities to the fixed contacts on the outside of one of the end plates. A suitable bracket member is secured to each of the shells and these are 50 so arranged that they may be connected together serially thereby combining several units into a complete assemblage.

The invention will be better understood from the following detailed description with

reference to the accompanying drawings in 55 which

Fig. 1 is a view in elevation showing the assembly of a pair of variable inductance units with a common operating shaft;

Fig. 2 is a longitudinal section through the 60 casing of one of the variable inductance units;

Fig. 3 is a cross sectional view taken along the line 5—5 of Fig. 2;

Fig. 4 is an end view of the inductance unit of Fig. 2; and

Fig. 5 is an enlarged longitudinal section 65 taken along the axes of the variable inductance.

In Fig. 1 two inductance units 36 are shown connected together and provided with a common shaft 17 which extends through the axes 70 of the two units.

Each unit consists of a tubular supporting member 37 of vulcanized fibre or other suitable insulating material on which are adjacently mounted a plurality of short tubular cores 38 on each of which is wound a coil, preferably of the honeycomb or duolateral type 39, 40, 41, 42, 43 and 44. The ends of the tubular supporting member 37 are seated in annular 80 grooves provided on the inner faces of the circular end plates 45 and 46 and a metal shell 47 is supported by the end plates 45 and 46 and forms therewith an enclosure for the coils 39 to 44 inclusive. A number of fixed contacts 48 are mounted in an arcuate row on the end plate 45 and are connected to the extremities and junctures of the coils 39 to 44 inclusive, as is quite clearly shown in Figs. 2 and 5. The shaft 17 carries a plurality of contact arms 49, 90 one for each inductance unit, each of which is adapted to wipe over its respectively associated set of fixed contacts 48. Electrical connections may be taken off from the shaft 17 by way of the binding posts 50, connector 51 and collar 52 which is secured to the shaft 17. A lead from one extremity of the coils is connected to the fixed terminal 53' mounted on the end plate 45.

To each of the shells 47 there is secured a 100 bracket member 53 by means of rivets 54 and these brackets are suitably proportioned as indicated in Fig. 1 for connecting the inductance units together in series. As many units as desired may thus be connected together and the 105 shaft 17 may be extended through all of the units.

A transformer having primary and second-

ary coils may be readily constructed by mounting an additional coil or coils in a structure similar to that illustrated.

The invention, as embodied in the apparatus, may take a number of alternative forms and is not to be limited except by the scope of the appended claims.

The multistage tuned radio frequency receiver system as set forth in the original application is claimed broadly in our application #67,184, filed Nov. 5, 1925, as a division hereof, and the system embodying transformer coupling is claimed in our application #278,236, filed May 16, 1928.

15 We claim:

1. In combination, a plurality of variable inductance devices each comprising a coil supporting member, one or more coils mounted on said supporting member, an enclosure for said 20 coil or coils and said supporting member including a pair of end plates, a set of fixed contacts on one of said end plates, and conductors connecting said coil or coils with said contacts, a shaft extending through and common to said 25 inductance devices, a plurality of contact arms secured to and rotatable with said shaft, each of said contact arms being individually associated with and adapted to wipe over one of said sets of contacts, a bracket member secured to each of 30 said inductance devices, said bracket members being arranged to be connected together in alignment end to end for supporting said inductance devices, a bracket member secured to each of 35 said inductance devices, said bracket members being arranged to be connected together end to end for supporting said inductance devices in alignment and means for connecting said bracket members together.

2. In combination, a plurality of variable inductance devices arranged in noninductive relation with respect to each other, and each comprising a coil supporting member, a number 40 of coils mounted on said supporting member, an enclosure therefor, a set of fixed contacts and conductors connecting said coils with said contacts, an actuator common to said inductance devices, a plurality of contact arms

45 rotatable with said actuator, each of said contact arms being individually associated with and adapted to wipe over one of said sets of contacts and said coils being designed and arranged for equal and simultaneous variation of the inductance in all of the devices.

50 3. A variable tuning device comprising a number of coil supporting means, a number of coils mounted on each of said coil supporting means, means for simultaneously and equally varying the inductance of the coils on each of 55 said coil supporting means, said coils being so mounted and connected that the adjustment of the coils on one of said coil supporting means has substantially no inductive coupling effect 60 on the coils on the other coil supporting means.

4. In combination, a plurality of variable inductance devices each comprising a coil supporting member, a number of coils mounted on said supporting member, an enclosure for each of the set of coils and its supporting member, a bracket member secured to each of 65 said inductance devices, said bracket members being arranged to be connected together in alignment end to end for supporting said inductance devices, means for connecting said bracket members together and a single means for simultaneously and equally varying the inductance of each inductance device.

70 5. A variable tuning device comprising a 75 plurality of variable inductance devices arranged in noninductive relation with respect to each other, and each comprising coil supporting means and a number of coils mounted thereon, and means for simultaneously and 80 equally varying the inductance of each of said inductance devices, the constants of said inductance devices being adapted to inter-tube coupling.

85 In testimony whereof we affix our signatures.

WILSON AULL, Jr.
